UNITED STATES PATENT OFFICE.

FRANK MALSCH, OF CAMDEN, NEW JERSEY, ASSIGNOR TO THE INDUSTRIAL MANUFACTURING COMPANY, OF CAMDEN, NEW JERSEY, A CORPORATION OF NEW JERSEY.

OVERSEAMING AND WELTING SEWING-MACHINE.

SPECIFICATION forming part of Letters Patent No. 758,264, dated April 26, 1904.

Application filed May 28, 1901. Serial No. 62,237. (No model.)

To all whom it may concern:

Be it known that I, FRANK MALSCH, a citizen of the United States of America, residing at Camden, in the county of Camden and State of New Jersey, have invented new and useful Improvements in Overseaming and Welting Sewing-Machines, of which the following is a specification.

My invention relates to overseaming sewing-machines especially adapted to hem or welt the edges of tubular knit goods, as sleeves of shirts, leggings, or hose, &c.; and it consists of stitch-forming and feeding devices especially adapted for this particular kind of work; and my invention further consists of the improvements hereinafter more fully described, and pointed out in the claims.

The invention will be more fully understood taken in connection with the accompanying drawings, forming part hereof, and in which—

Figure 1 is a front elevation of a machine embodying my invention. Fig. 2 is a sectional plan view taken above the cloth-plate. Fig. 3 is an end elevation of the machine, the horn or sleeve-support being removed. Fig. 4 is a section substantially on the line 4 4 of Fig. 1. Fig. 5 is a section on the line 5 5 of Fig. 1. Fig. 6 is a section on the line 6 6 of Fig. 1. Fig. 7 is a top view of the machine. Fig. 8 is a plan view showing the presser-foot, welter, and mechanism on top of the cloth-plate. Fig. 9 is a front view of the welter. Fig. 10 is a front view of the thread-carrying looper and its mechanism, showing the same in a depressed position and ready to take loop from the stitching-needle. Fig. 11 is a similar view. Fig. 12 is a view of a welted edge of a piece of fabric when being trimmed and sewed. Fig. 13 is a view of a piece of fabric, showing the finished hemmed edge. Fig. 14 is a perspective view of the stitch-forming mechanism, showing the relative positions thereof when manipulating the two sewing-threads; and Fig. 15 is a similar view.

Referring now to the drawings for a further description of my invention, A is the base of the machine; A', the machine-arm; B, the main shaft; C, the cloth-plate with horn or sleeve-

support c^o, and E the needle-bar. This needle-bar E is arranged in a slanting position, leaning with its upper end toward the rear in order to bring the needle e into operative position with a thread-carrying looper d and a loop-spreader s, as will be more fully described. The needle-bar E is mounted in guides a on the machine-arm A' and receives oscillatory motion from a rock-shaft H, which is driven from the main shaft B by the eccentric b¹, eccentric-strap b², and arm h¹ of the rock-shaft H. The upper end of the eccentric-strap b² is adjustably secured to the said arm h¹ in order to vary the throw of the needle-bar E, which is connected to the rock-shaft H by means of the arm h² and link e'. 50 55 60 65

The thread-carrying looper d operates in a vertical plane parallel with the main shaft and in rear of the stitching-needle e. This looper consists of a T-shaped lever, whose upper end is adapted to carry a thread and engage a loop 70 of the thread of the stitching-needle e. At its stem d¹ the looper d is pivoted to one end of a link d², which latter is hinged with its other end d³ to the base of the machine. The lower end d³ of the looper d is pivoted to a vibrating double-armed lever d⁴, trunnioned to the machine-base at d⁵ and receiving its motion from the rock-shaft H by means of the connecting-rod d⁶ and arm h³. This arrangement 75 80 85 of the thread-carrying looper d permits the same of having its upper end almost vertical and directly at the left side of the needle e when at its lower position, as shown in Fig. 10, and when moving upward it passes toward the right of the needle and keeps in proximity to the same, so that the stitch mechanism occupies but little room in order to place hose or sleeves of small diameter over the horn c^o to have their edges trimmed and welted. 90

The loop-spreader s is located entirely above the cloth-plate and moves in a horizontal plane to take a loop from the thread-carrying looper d and present it to the stitching-needle e, as will be further described. This loop-spreader s is provided with a vertical shaft s', journaled in a bearing of the machine-arm A', and on the upper end of this shaft is attached an arm s² to actuate the said spreader s. Motion is im- 95

parted to the shaft s' from the main shaft B by an eccentric b^3 , eccentric-strap b^4 , bell-crank lever b^5 , journaled at a^9 to the machine-arm A'. The upper end of this lever b^5 is connected to the free end of the arm s^2 of the loop-spreader shaft s' by the connecting-rod s^3 , and in each revolution of the main shaft B the spreader s is brought once into proximity to the stitching-needle e and back to its starting-point.

The feed-bar f is slotted and straddles with its front end an eccentric f^1 of the main shaft B to raise and lower the said feed-bar. The rear end of the feed-bar f is hinged to a vertical plate f^2 , journaled at f^3 to the machine-base A, and is provided with a slotted extension f^4 , to which one end of a connection-rod f^5 is adjustably secured. On the machine-base A is fulcrumed a swinging lever f^6 , which is pivotally secured at its upper end to the said connection-rod f^5 and provided with a sliding eccentric-box f^7 , mounted over an eccentric f^8 on the main shaft B to actuate the said plate f^2 and with it the feed-bar f . By the means just described a very accurate and positive feed, driven at a high speed, is obtained.

The pressure-foot p is secured to the lever p' , hinged at p^2 to the cloth-plate C, and a handle p^3 is pivotally connected to the arm to raise the said foot p against the action of the spring p^4 . This presser-foot is also provided with a finger p^5 , over which the overseam-stitches are formed and cast off, and with a recess p^6 for the upper movable and actuating trimmer-blade t . The trimmer shown in the accompanying drawings of this application is made the subject of a divisional application for patent filed July 1, 1902, Serial No. 114,028, and does not form a part of this application; but for making the operation of this machine clear it is deemed advisable to give a description of such trimmer. This trimmer-blade is secured to a reciprocating block t^2 , moving in guides t^3 of a block t^4 , secured adjustably to the machine-arm A'. The latter is provided with a groove t^5 , into which a key of the block t^4 fits, so that the same, with the trimmer-blade t , may be moved closer to or farther away from the needle e in order to change the width of the seam or welt.

The reciprocating block t^2 is actuated from the rock-shaft H by means of a gear-sector h^4 on said shaft and meshes with a toothed lever h^5 , pivoted to the machine-arm A'. A link h^6 connects the said lever with the said block t^2 and operates the trimmer-blade t vertically. The blade t can also be adjusted vertically and is mounted in a V-shaped groove t^7 of the block t^2 , in which groove it is held by the screw t^8 . The lower end of this blade t operates in a slot t^{10} , provided in the upper end of a vertically-arranged arm t^9 , pivoted at t^8 to the machine-bed A. This arm t^9 is not fastened anywhere except at its pivotal connection,

which allows it to follow the upper operating-blade t when adjusted to any width of seam, and it may be remarked that one corner of the upper blade t is always in engagement with the slotted arm t^7 , as shown in Fig. 3. To lead the trimmed-off material away, a chute t^{11} is provided and fastened to the cloth-plate C.

The welter W may be of any suitable shape and construction, but preference is given to the one shown in Figs. 8 and 9 as being simple and efficient. The bracket w is adjustably secured to the cloth-plate C and is provided with a bent plate w' , adapted to fold the edge of the fabric into the shape shown in Fig. 12, the finger or projection w^2 serving to accomplish this result.

The operation of my improved overseaming and welting machine is as follows: A sewing-thread n is led through the guide n' , tension device n^2 , guide n^3 to the stitching-needle e , and another thread r is led through the guide r' , tension device r^2 , eye r^3 , eye r^4 on the thread-carrying looper d , and through the upper eye thereof. The edge of the fabric x is then bent as shown in Fig. 12 and inserted into the welter w , Figs. 8 and 9. The machine is then started, and as the stitching-needle e , with its thread n , penetrates the fabric the thread-carrying looper d is in a position to the left of the needle and just back of the same, as shown in Fig. 10. The looper d then engages the loop at the back of the needle and moves with the same upward and to the right of the needle, as shown in Fig. 14. In this position the needle e has moved upward and the loop-spreader s has moved close to the thread-carrying looper d , from the rear of which it takes a loop of the thread r and presents the same to the stitching-needle e , as shown in Fig. 15, so that when the latter again descends it fastens the loop of the thread r to the top of the fabric, forming the stitch, as clearly shown in Figs. 12, 14, and 15. After the seam is finished the welt is turned over in the manner shown in Fig. 13.

It will be understood by those skilled in the art to which my invention appertains that modifications may be made without departing from the spirit of the invention.

Having thus described the nature and objects of my invention, what I claim as new, and desire to secure by Letters Patent, is—

1. In an overseam sewing-machine, having a reciprocating thread-carrying stitching-needle slanting with its upper end toward the rear of the machine its complementary actuating and feed mechanism and tongued presser-foot and throat-plate, the combination with a thread-carrying looper formed integral with a T-shaped lever adapted to move said looper upward and longitudinally in a vertical plane intersecting the line of travel of the slanting stitching-needle, of a loop-spreader and means for reciprocating the same in a horizontal plane above the cloth-plate, so that its free

end passes in proximity and in front of the stitching-needle to engage the thread of the loops carried by the looper and convey the same over the top of the presser-foot, where 5 it will be secured by the needle, substantially as and for the purposes set forth.

2. In an overseam sewing-machine, in combination with a suitable feeding device, a reciprocating thread-carrying stitching-needle slanting with its upper end toward the rear of the machine, a throat-plate and a presser-foot, a tongue on each of said throat-plate and presser-foot, of a thread-carrying looper moving in a vertical plane, a vibrating arm, 15 whose free end is pivoted to the lower end of said looper, a link pivoted with one end to the machine-base and having its other end connected with an extension or lug of the said looper, and a loop-spreader operating in a horizontal plane above the cloth-plate, substantially as and for the purposes set forth. 20

3. In an overseam sewing-machine, in combination with a suitable feeding device, a reciprocating thread-carrying stitching-needle, a throat-plate and presser-foot, of a thread-carrying looper, a vibrating double-armed lever having its free end pivoted to the lower end of said looper, a link pivotally connected at one end to the machine-base and at its other to the said looper at a point above the connection with the said arm, a loop-spreader operating in a horizontal plane above the cloth-plate, a vertical shaft for said spreader and means for rocking said shaft, substantially as and for the purposes set forth. 25 30 35

In witness whereof I have hereunto set my hand in the presence of two subscribing witnesses.

FRANK MALSCH.
